SHEET METAL TERMINAL CONNECTOR

Ougljesa Jules Ponpitch, Chicago, Ill., assignor to Illinois Tool Works, Chicago, Ill., a corporation of Illinois

Application April 20, 1950; Serial No. 157,171

2 Claims. (Cl. 339—95)

This invention relates generally to electrical connectors, and more particularly to electrical connectors of the type adapted to effect connection with an electrical conductor by the mere longitudinal insertion of the conductor within the connector.

Electrical connectors have heretofore been employed which require crimping of the connector stock or the application of solder to complete electrical coupling with a conductor such as the free end of a wire or cable. It is an important object of the present invention to avoid the necessity of stock crimping or solder, and to this end the invention contemplates an electrical connector capable of being formed from a single sheet of stock and so designed as to effect positive electrical contact with a conductor element by merely inserting the free extremity of the conductor within an elongated connector section.

More specifically, the invention contemplates an electrical connector of the type referred to above, in which, as a result of the longitudinal insertion therein of the free extremity of a wire or cable, connector teeth will aggressively contact the conductor, and the connector will yieldably urge the conductor into contact with said teeth.

It is a further object of the present invention to provide an electrical connector as above outlined, which may be produced by very simple stamping and forming methods, said connector being formed from a single piece of sheet metal stock and equipped with mounting sections of various designs to accommodate the requirements of the device to which the connector is to be attached.

The foregoing and other objects and advantages will be more apparent from the following description when considered in connection with the accompanying drawings, wherein:

Fig. 1 is a perspective view of an electrical connector which is representative of one embodiment of the invention, said connector being shown with the free end of a conductor wire coupled thereto.

Fig. 2 is an enlarged central vertical sectional view of the electrical connector shown in Fig. 1, said view being taken along the line 2—2 of Fig. 4.

Fig. 3 is a plan view of the electrical connector shown in Figs. 1 and 2;

Fig. 4 is an end view of the connector taken substantially along the line 4—4 of Fig. 2;

Fig. 5 is a plan view of the blank or stamping from which the connector of Figs. 1 to 4, inclusive, may be produced;

Fig. 6 is a plan view of a slightly modified embodiment of the invention, wherein a pair of connector accommodating sections extend from opposite sides of a central mounting section;

Fig. 7 is a side elevational view of the device shown in Fig. 6;

Fig. 8 represents a still further modification somewhat similar to the form shown in Figs. 6 and 7, but differing therefrom in the use of a central mounting section of reduced size;

Fig. 9 is a side elevational view of the device shown in Fig. 8;

Fig. 10 is an enlarged sectional view taken substantially along the line 10—10 of Fig. 3 illustrating the manner in which the struck out teeth aggressively impinge a peripheral portion of the conductor, and the wing portions yieldably bear against the oppositely disposed peripheral surface areas of the conductor;

Fig. 11 is a plan view of a modified form of the electrical connector contemplated by the present invention,

2

wherein the conductor engaging teeth are struck out of the wings, as distinguished from the base of the connector.

Fig. 12 is an enlarged transverse sectional view of the device shown in Fig. 11;

Fig. 13 is a plan view of a still further modified form of the connector designed to accommodate a pair of the conductors;

Fig. 14 is an enlarged transverse sectional view taken substantially along the line 14—14 of Fig. 13;

Fig. 15 is a transverse sectional view similar to Fig. 14 illustrating a connector for accommodating a pair of conductors, wherein the struck out teeth are provided in the base portion; and

Fig. 16 is a plan view of another modified form of the connector capable of accommodating conductors inserted from opposite ends thereof.

Referring now to the drawing more in detail, wherein like numerals are employed to designate similar parts throughout the various figures, it will be seen that the embodiment of the electrical connector illustrated in Figs. 1 to 4, inclusive, and Fig. 10, is designated generally by the numeral 12. The connector 12 includes an elongated conductor accommodating section 14 and a mounting section 16 formed integral with the section 14 and extending laterally thereof.

The section 14, the cross section of which is more clearly illustrated in Fig. 10, includes a sheet metal base plate or portion 18 having struck out teeth 20 spaced longitudinally thereof and extending out of the plane of the plate 18 a sufficient distance to impinge the periphery of an electrical conductor or wire 22. Formed integral with and extending from each margin of the base plate 18 are resilient wing elements 24. These wing elements 24 are inclined toward each other so as to cooperate with the plate 18 in presenting a longitudinal channel or area for accommodating the conductor 22. The inner surfaces of the wing elements 24 adjacent the free margins thereof are normally spaced from the teeth 20 a distance which requires said wing elements to flex outwardly upon the insertion of the free extremity of the conductor 22. Thus, these wing elements serve to yieldably urge the conductor into aggressive impingement with the teeth 20.

To lend transverse rigidity to the base plate 18, the opposed longitudinal margins thereof are preferably bent out of the plate stock so as to provide ribs 26, Fig. 10. Thus, ribs serve as the connecting hinge, as it were, between the plate 18 and the wing elements 24.

The connector mounting section 16 in the disclosed embodiment, extends substantially normal to the plane of the plate 18, and is provided with an aperture 28 to facilitate mounting of the connector upon the device in which it is to be incorporated. At the junction of the plate 18 and the mounting or anchoring plate 16 is formed a stiffening rib or boss 30. This serves to stiffen the parts against angular displacement with each other. Also, on opposite sides of the central rib 30 flange sections 32 cooperate in strengthening the connection between the section 14 and the section 16. Obviously, the invention contemplates various forms of mounting or anchoring sections, depending upon the environment in which the connector is to be employed.

It will be noted that the teeth 20 are so formed they not only serve aggressively to impinge the conductor 22 and thereby establish positive electrical contact, but they also are so formed as to permit longitudinal insertion of the conductor 22 into the connector section 14 (namely, to the left, Figs. 2 and 3) and likewise to resist forces tending to retract the conductor.

Thus, the conductor accommodating section of the connector contemplated by the present invention serves automatically to lock a conductor in place and simultaneously establish positive electrical contact without the necessity of crimping, soldering or the like.

In Figs. 6 and 7 a slightly modified form of connector 75 is shown. This connector is designated generally by the numeral 12a and includes a pair of oppositely disposed conductor accommodating sections 14a. The elements constituting these locking sections 14a are identical with the corresponding elements of the sections 14 previously described, and hence are designated by corresponding numbers bearing the suffix *a*.

The mounting or anchoring portion of the connector 12a is designated by the numeral 16a and is provided with an aperture 28a to facilitate mounting thereof.

The connector 12b illustrated in Figs. 8 and 9 is identical with the connector 12a just described, except that the central mounting section 16b is not apertured and consists merely of a narrow strip, as distinguished from the relatively wide apertured mounting section 16a. The other elements of the connector 12b are illustrated by corresponding numbers bearing the suffix b.

In Figs. 11 and 12 a further modified form of the connector is shown and is designated generally by the numeral 12c. This connector 12c is similar to the connector 12, differing only therefrom in the provision of struck out teeth 20c in the wings 24c, as distinguished from the teeth 20 of the connector 12 which are struck out from the base. All other parts of the connector 12c are given numerals with the suffix c corresponding to the numerals used in identifying the parts of the connector 12. It will also be noted that the base portion 18c is preferably depressed along its central portion to accommodate the periphery of the conductor 22.

Figs. 13 and 14 illustrate a further modified form of the connector designated generally by the numeral 12d. The connector 12d differs from the previously described connectors in that it is designed to accommodate a pair of conductors inserted from one end thereof. The base 18d is provided with a central bead or rib 34 which separates the connector into a pair of longitudinal chambers for accommodating the conductors 22. The teeth 20d are struck out from the wings 24d and cooperate with the base 18d in securing the conductors against inadvertent longitudinal displacement.

Fig. 15 is a transverse sectional view similar to Fig. 14 disclosing a conductor 12e which differs structurally from the conductor 12d in providing the struck out teeth 20e in the base portion 18e, as distinguished from the connector 12d.

Fig. 16 discloses a connector 12f designed to accommodate conductors inserted from opposite ends thereof. It will be noted that the struck out teeth 20f on one of the wings 24f extend in a direction to permit insertion of the conductor from one end of the connector, and the teeth 20f in the other wing are disposed so as to permit insertion of the conductor from the opposite end of the connector. In this manner the connector 12f may serve as a coupling between a pair of conductors. The connector 12f does not incorporate any auxiliary structure for mounting the device in position. Such a structure could, of course, be employed in instances where necessary.

From the foregoing it will be apparent that the present invention contemplates an electrical connector of extremely simple and practical construction capable of being produced from sheet metal stock by the practice of simple stamping and forming operations. It will also be apparent that a single connector constructed in accordance with the present invention may be used to accommodate conductors of varying sizes. In other words, the yieldability of the wing elements makes it possible to insert the free extremities of wires or cables of varying diameters without the necessity of employing a connector of more than one size. These yieldable wing elements cooperate efficiently to urge a complementary conductor against the teeth in the base plate. Also, the disposition or inclination of the struck out portions of the base plate facilitate the ease with which the conductor may be inserted within the connector, and after insertion these teeth serve aggressively to resist longitudinal

retraction of the conductor. Obviously, the connector may be made in various sizes, shapes and forms in order to adapt its application to the electrical device upon which it is to be mounted. Thus, the conductor accommodating section or sections may be combined with mounting or anchoring sections of a wide variety of shapes and forms without departing from the scope of the present invention.

While for purposes of illustration certain specific embodiments have been disclosed herein, it will be understood that other modifications and changes may be made without departing from the spirit and scope of the appended claims.

The invention is hereby claimed as follows:

1. A one-piece sheet metal electrical connector for permanent attachment with an electrical conductor, and comprising a base portion and integral resilient wing portions along substantially the entire extent of the longitudinal margins of said base portion, the said wing portions being inclined away from the base portion and having the free edges thereof disposed in directions approaching one another and forming with said base portion a housing to receive inserted conductors of cross-sectional sizes sufficient to urge the wing portions outwardly to stressed conditions exerting components of force toward the base portion for clamping the conductor therebetween, the wing portions and base portion forming said housing having inner surfaces providing three-surface longitudinal engagement for an inserted conductor, at least one of said surfaces having spaced substantially rigid integral teeth disposed substantially throughout the length thereof struck from within the confines thereof with transversely extending biting free edges projecting away from the entry end of the housing to facilitate the insertion of the conductor and urge the wing portions outwardly, another of said surfaces providing continuous surface contact with the inserted conductor throughout the longitudinal extent of said spaced teeth and in substantial opposition thereto for impressing uniform pressure on the conductor throughout the longitudinal extent of the spaced teeth to assure uniform biting action of each of the teeth into the conductor and thereby ensuring good electrical contact, and means associated with the housing for providing connection with another electrical conductor.

2. A one-piece sheet metal electrical connector as claimed in claim 1 wherein the means providing the connection with another electrical conductor comprises a mounting flange angularly disposed with respect to said housing and wherein there is provided a rib traversing the juncture angle between the housing and mounting flange for resisting relative displacement therebetween.
